UNITED STATES PATENT OFFICE.

CHARLES O. ROE, OF INDIANAPOLIS, INDIANA.

TRENCH-SANDAL.

1,276,964.

Specification of Letters Patent. Patented Aug. 27, 1918.

Application filed October 22, 1917. Serial No. 197,829.

To all whom it may concern:

Be it known that I, CHARLES O. ROE, a citizen of the United States, residing at Indianapolis, in the county of Marion and State of Indiana, have invented certain new and useful Improvements in Trench-Sandals, of which the following is a specification.

This invention relates to sandals to be worn with boots or shoes for trench work in warfare and also in peaceful pursuits when walking over rough, icy and uneven slippery ground.

One of the objects of the invention consists in the provision of a sandal to be worn with boots and shoes, which will stand far greater and harder usage than leather; which will give the wearer a firmer footing under all kinds of ground and weather conditions; also preventing the wearers' feet from becoming sore by reason of the soles of the boots and shoes wearing thin, thereby promoting and maintaining a healthier condition of the feet, and also retarding fatigue of the wearers, by maintaining a better equipoise of the body.

A further object of the invention consists in the provision of a sandal wherein worn down spikes in the soles can be easily and readily replaced, thereby prolonging the life and utility of the sandal with a corresponding reduction in cost of replacement and maintenance.

I accomplish the above objects of the invention, and such others as may appear from a perusal of the specification and claims, by means of the construction illustrated in the accompanying drawing, forming a part hereof, in which—

Figure 1 is a side elevation of my improved sandal, showing the manner in which the same is held in position on the wearer's foot. Fig. 2 is an underside plan view of the sandal. Fig. 3 is a top or plan view of the sandal. Fig. 4 is a fragmentary detail cross sectional view, on an enlarged scale, showing one of the locking devices, on a line 4—4 in Fig. 3. Fig. 5 is a fragmentary detail longitudinal sectional view, on an enlarged scale, showing more clearly the construction and arrangement of the parts. Fig. 6 is a fragmentary detail perspective view, showing the manner in which the counter of the sandal is attached to the sole-plate. Fig. 7

is a perspective view of one of the spikes, 55 the remaining parts being omitted.

Referring to the drawings, the sole and heel of the sandal are preferably composed of thin sheet steel plates to sustain the rough usage to which they are subjected. 60 The sole of the sandal is composed of at least three sections 10, 11 and 12 which are hingedly secured together by means of the hinge-connections 14 and 15. The hinge-connections 14 and 15 extend transversely 65 of the sandal and are located immediately beneath the ball of the foot where the greatest amount of bending occurs, and where the greatest amount of elasticity is required. The free end of section 10 is bent downwardly at right angles to provide an extension 16 which is slightly less the height of the heel on the shoe, thereby providing some latitude for the wearing down of the heel. 70 Section 17 which forms the heel of the sandal is bent upwardly at one end to form a member 18 which member rests against extension 16, and member 18 is bent at right angles to form a member 20 which rests against the outer surface of section 10 of the sole, and members 16 and 18, and, also, members 10 and 20 are rigidly secured together by means of suitable rivets, or by spot-welding. 75 This overlapping of sections 10 and 17 reinforces the sandal at its weakest point— 80 where the sole and heel sections join. Section 12 of the sole is provided with a shoe-tip 22 to form a pocket for the toe of the boot or shoe, and the heel section 17 is provided with a counter 21 for holding the boot or shoe in position in the sandal. Counter 21 is provided on opposite sides with a slot 21^a adapted to receive a strap 23, the latter 85 passing over the instep of the foot and serves to hold the sandal in operative position, on 90 the boot or shoe. In addition to strap 23 I provide a strap 24 which passes over the ball of the foot and engages the ears 26 formed integrally with section 11, and also with the ears 27 formed integrally with section 12 of 95 the sole. Heel-section 17, sole sections 10, 11 and 12 are provided with a plurality of apertures 30, and through these apertures I pass suitable tempered steel spikes 31. 100 Spikes 31 are provided with thin flat heads 105 32 so as to extend but a short distance above the surface of sections 10, 11, 12 and 17. Spikes 31 are easily removed from apertures

30 when worn down to where their utility is destroyed and may be easily replaced by the introduction of new spikes 31 into apertures 30, thereby making the sandals as effective 5 as when new. Spikes 31 are prevented from backing out or being displaced from apertures 30 by means of suitable plates which rest tightly upon the flat heads of said spikes. To render the plates to be more 10 easily removed and inserted they are preferably divided along their longitudinal centers into two members, in which the sections 35 and 36 are arranged within the heel portion of the sandal; members 37 and 38 15 being arranged in section 10 of the sole, and members 39 and 40 in section 12 of the sole. Section 11 is provided with a single member 41, the latter being narrow and easily sprung upward in the center to remove it, so that 20 this member may be made of a single piece of material. The outer edges of heel-members 35 and 36 are held down into contact with the heads of the underlying spikes 31 by means of the marginal ears 45 which are 25 formed out of the adjacent edges of heel sections 17, these ears being bent downwardly to form hooks under which the edges of members 35 and 36 are inserted. The outer edges of members 37, 38, 39, 40 and 41 30 are held down by the hooks 44 which are formed by up-turning the edges of said plates. The meeting edges of members 35, 36, 37, 38, 39 and 40 have co-operating depressions 46, and these meeting edges in the 35 bottoms of these depressions are provided with notches to form elongated slots 47. Extending through each slot 47 is a locking pin 48, these pins being mounted in sections 10, 11, 12 and 17. Pins 48 are provided 40 on their lower ends with heads 49 to prevent their displacement from said sections, the pins however being free to rotate about their longitudinal axes. The upper end of each pin 48 terminates in a transverse head which 45 projects laterally away from its opposite sides, and each head is provided in its top surface with a kerf 51, adapted to receive the end of a screw-driver, or similar tool, for rotating pins 48 so as to move heads 50 50 to stand either transversely across the edges to lock the plates or parallel with slots 47 to permit the removal of the plates.

By means of the herein described construction, the plates may be easily unlocked and 55 taken out for the removal and replacement of spikes 31, when the latter have become sufficiently worn to be unfit for further service.

Having thus fully described my said in-

vention, what I desire to secure by Letters 60 Patent, is—

1. A sandal of the herein described class comprising a sole-member composed of a plurality of hingedly connected sections containing a plurality of perforations, spikes 65 passing through said perforations, means formed along the edges of said sole-member for securing the marginal edges of a spike-retaining means, a spike-retaining means adapted to be inserted under the preceding 70 means and resting upon the upper ends of the spikes for holding the latter in operative position, and means for locking said spike-retaining means in operative position.

2. A sandal of the herein described class 75 comprising a sole-member composed of a plurality of hingedly connected sections containing a plurality of perforations, a heel-member attached to the adjacent sole-section and provided with perforations, 80 spikes passing through said perforations, retaining-means for holding the spikes in operative position, and means for locking said retaining-means in operative position.

3. A sandal of the herein described class 85 comprising a sole-member composed of a plurality of hingedly connected sections containing a plurality of perforations, a heel-member provided with perforations attached to the adjacent sole-section, spikes passing 90 through said perforations, spike-retaining means for holding the spikes in operative position, means arranged along the outer edges of the heel and sole members for securing the marginal edges of the spike-retaining means in operative position, a spike-retaining means, and means for locking the spike-retaining means in operative position.

4. A sandal of the herein described class comprising a sole-member composed of a 100 plurality of hingedly connected sections containing a plurality of perforations, spikes passing through said perforations, spike-retaining means for holding said spikes in operative position and provided with slots, 105 pins arranged in said sole-member and extending through said slots, transverse heads on said pins for locking the spike-retaining means when the heads stand transversely of said slots, and means for securing the 110 marginal edges of said spike-retaining means in operative position.

In witness whereof, I, have hereunto set my hand and seal at Indianapolis, Indiana, this 20th day of October, A. D. one thousand nine hundred and seventeen.

CHARLES O. ROE. [L. S.]
